The ornamental design for a modular wall nesting system, as shown and described.

DESCRIPTION

FIG. 1 is a perspective view of a modular wall nesting system showing the design as used in a modular wall;

FIG. 2 is a perspective view thereof;

FIG. 3 is an exploded view thereof;

FIG. 4 is a front elevational view thereof;

FIG. 5 is a rear elevational view thereof;

FIG. 6 is a left elevational view thereof;

FIG. 7 is a right elevational view thereof;

FIG. 8 is a bottom plan view thereof; and,

FIG. 9 is a top plan view thereof.

The broken lines are for illustrative purposes only and form no part of the claimed design.
